UNITED STATES PATENT OFFICE.

JAMES C. CRITCHETT, OF EL PASO, TEXAS.

FLYING-MACHINE.

1,294,774.

Specification of Letters Patent.

Patented Feb. 18, 1919.

Application filed March 11, 1918. Serial No. 221,827.

To all whom it may concern:

Be it known that I, JAMES C. CRITCHETT, a citizen of the United States, residing at El Paso, in the county of El Paso and State of Texas, have invented certain new and useful Improvements in Flying-Machines; and I do hereby declare the following to be a full, clear, and exact description of the invention, such as will enable others skilled in the art to which it app pertains to make and use the same.

The present invention relates to improvements in flying machines, and has for an object to provide an improved flying machine having a framework built up in the shape of one or a plurality of tetrahedral figures, whereby a relatively small flying machine may be constructed in the form of a single tetrahedron, while larger machines may be produced by enlarging upon the smaller framework without alteration. By this means the tetrahedron forms a standardized unit for flying machines of small or large size, and the work of constructing and assembling the parts is simplified and rendered expeditious.

Another object of the present invention resides in providing a flying machine with a framework in which the component members are united after the fashion of a tetrahedral figure, thereby securing great strength with little strain on the individual members of the framework, enabling the use of inferior material to that necessary for the present construction of aeroplanes, and eliminating the necessity for that careful selection of material that is at present practised.

A further object of the present invention resides in providing a flying machine which will combine great strength with lightness, and have increased carrying capacity.

It is a further object of the present invention to provide a flying machine in which the framework will afford one or more convenient and strong locations for fuselage, platforms, power plants, etc.

In the accompanying drawings forming a part of this application, and in which similar reference symbols indicate corresponding parts in the several views:

Figure 1 is a side elevational view of one form of flying machine constructed in accordance with my present invention.

Fig. 2 is a rear elevational view thereof. 55

Fig. 3 is a top plan view of the flying machine; and

Fig. 4 is a diagrammatic perspective view of a fragment of the machine framework.

In Figs. 1, 2 and 3 of the drawings is 60 shown a flying machine, the framework whereof is constructed in the shape of three tetrahedral figures located side by side and having parts thereof in common.

Referring in detail to the construction, 1 65 designates the lower edge member of the central portion of the framework; while 2 and 3 represent the edge members of the tetrahedral portions of the lateral parts of the framework. At 4 and 5, in Fig. 3, are 70 shown the forward edge members which connect with the front end of the lower edge member 1 at 6, and which diverge and extend upwardly and at an inclination rearwardly. Similar rear edge members 7 and 75 8 are shown in Figs. 2 and 3 to be coupled to the rear end of the lower edge member 1, and diverge upwardly and extend forwardly.

The front edge members 4 and 5 and 80 the rear edge members 7 and 8 of the central portion of the tetrahedral framework do not merge upwardly into a single edge member, but the top prism of the tetrahedron is truncated, as indicated in Fig. 85

1, and the front edge members 4 and 5 are joined together by a horizontally extending tie-rod 9; while the upper ends of the rear edge members 7 and 8 are similarly connected by a horizontal tie-rod 10 90 running parallel with the tie-rod 9. The left ends of the tie-rods 9 and 10, in Fig. 3, together with the upper ends of the front edge member 4 and rear edge member 7, are connected to another horizontal tie-rod 95 11. At 12 is shown a tie-rod parallel to the tie-rod 11, and serving to join the right-hand ends of the tie-rods 9 and 10 and the upper ends of the front edge member 5 and rear edge member 8. These several tie-rods 100 9, 10, 11 and 12 provide a horizontal frame forming the upper end of the central tetrahedral part of the machine framework.

A series of struts 13 are connected between separated and preferably equidistant points 105 14 and 15 along the forward edge member 4 and horizontal tie-rod 9; and a similar series of struts 16 are coupled between the

points 15 along the horizontal tie-rod 9 and separated and preferably equidistant points 17 on the forward edge member 5. The construction is such that the struts 13 and 16 5 will intersect in the manner shown.

In a similar way, there are series of struts 18 and 19 connected between points along the rear edge members 7 and 8 and the horizontal tie-rod 10, as will be clear from Figs. 10 2 and 3.

Similarly, the other faces of the tetrahedral central framework comprised between the edge members 1, 4 and 7, and 1, 5 and 8, are supplied with struts in a like order 15 and arrangement.

The lateral portions of the framework are similarly built up in tetrahedral formation, 20 and 21 indicating forward edge members at the left part of the machine, and 22 and 23 rear edge members, all of which are connected at their lower ends to the lower edge member 2. The upper ends of these edge members 20, 21, and 22, 23, are connected by 25 projections of the horizontally extending tie-rods 9 and 10.

At the opposite side of the framework the forward edge members are represented at 24 and 25, and the rear edge members at 26 and 27, all of which are joined to the lower edge member 3. Similar extensions of the tie-rods 9 and 10 serve to connect the upper ends of such edge members 24, 25, and 26, 27.

The upper ends of the forward edge members 21 and 24, and the forward ends of the rear edge members 23 and 26, are connected together by a horizontal tie-rod 28 which forms a common part of the two lateral tetrahedral frames, and in which these frames coincide. 29 and 30 represent tie-rods that 40 join, respectively, the upper ends of the front and rear edge members 20 and 22, and 25 and 27, and which form with the common tie-rod 28 and the projections of the rods 9 and 10, horizontal frames forming the upper 45 part of the combined framework.

Lying in that face of the left lateral part of the framework which is comprised between the edge members 20 and 21 and the projection of the tie-rod 9, are two series of 50 struts 31 and 32, which are connected in a manner similar to the struts as above described.

Struts 33 and 34 of a similar character, lie in the face comprised between the rear edge members 22 and 23 and the projection of the tie-rod 10.

At the right side of the frame there are similar struts 35, 36 and 37, 38.

Having reference now to the side elevational view shown in Fig. 1, which shows the face of the right portion of the framework comprised between the edge members 3, 25 and 27 and the upper horizontal tie-rod 30, 39 and 40 designate other struts lying in the 60 plane of this face and intersecting in a man-

ner similar to the other struts as hereinbefore described.

It will be noted from an inspection of Figs. 2 and 3, that the upper portions of the diverging edge members form parts of overlapped tetrahedral figures, and act in the capacity of struts for adjacent tetrahedral frames. 70

As seen in Figs. 1 and 3, it will be plain that there are provided other horizontal tie-rods 41, 42 and 43, in any suitable number, 75 extending in parallelism with the upper tie-rod 30, and connected between points on the edge members 25 and 27, at which points the ends of the struts 39 and 40 join thereto. 80

Figs. 2 and 3 show similar tie-rods 44, 45 and 46, connected between the rear edge members 26 and 27, and connected thereto at points where the ends of the struts 37 and 38 join therewith. In Fig. 3 alone are shown 85 the tie-rods 47, 48 and 49, they being connected between points on the forward edge members 24 and 25, where the struts 35 and 36 are attached thereto. Also, in Fig. 3, may be seen the tie-rods 50, 51 and 52 which connect between the front edge member 24 and rear edge member 26 at points thereon where the struts lying in these faces are attached, but which struts are not shown in the drawings. 95

The various tie-rods above described combine to form horizontal frames which pass through the body of the tetrahedral framework, and which brace the same and impart strength and rigidity thereto. For instance, 100 the tie-rods 41, 47, 50 and 44 form one of such horizontal frames. A second horizontal frame is formed by the tie-rods 42, 48, 51 and 45. A third such frame, in the right lateral tetrahedral portion of the framework, 105 is composed of the tie-rods 43, 49, 52 and 46.

Now, referring for clearness to the diagrammatic showing in Fig. 4, I also preferably provide a series of tie-rods or wires 53, 110 lying in the several horizontal frames just referred to and passing through the body of the tetrahedral framework, such rods or wires 53 being connected between parts of such horizontal frames; for instance, the 115 horizontal tie-rods 44 and 47, as shown in Fig. 4. These rods or wires 53 preferably extend in parallelism, and are joined to such tie-rods 44 and 47 at points therein where the struts intersect. The struts 37 and 38, 120 at their intersections with the rods 44 and 53, may be connected to such rods in order to form a well bound and strong construction.

The right hand lateral part of the framework has been above described, and as the central and opposite portions of such framework are similar with respect to the tie-rods, horizontal frames and wires, it is thought unnecessary to repeat the description for such parts. 125

The central tetrahedral framework is projected rearwardly to provide a steering tail 60 having the rudder 61 and elevators 62. This steering tail is composed of a lower member 63, which is a projection of the lower edge member 1 of the central part of the framework, the upper central member 64 and lateral members 65, 66, and 67, 68, disposed to opposite sides of the members 63 and 64; these members being projections of the tie-rods which form parts of the horizontal frames of the central tetrahedral framework. Similar diagonal and intersecting braces 69 and 70 are connected between the several parts of the steering tail.

The aeroplane framework is provided with suitable sustaining planes, there being four such in the present drawings, which planes are cambered and mounted in the framework in stepped relation. The top plane 71 extends across the machine between the tie-rods 29 and 30. The second plane 72 is set slightly to the rear with respect to the plane 71 above, and is shorter in length, as required by the tetrahedral shape given the framework. In a like manner the third plane 73 is set a similar distance to the rear of the second plane 72, and is still shorter. The fourth plane 74 is at the lower rear part of the framework to the rear of the plane 73 immediately above it, and of the shortest length.

Each of the tetrahedral portions of the framework may be provided with complete power plants 75, 76 and 77, with individual propellers 78, 79 and 80, and each portion of the framework is furnished with its individual float 81, 82 and 83, respectively, together with the ground wheels 84, 85 and 86. The central steering tail is also furnished with a float 87. In a similar way each part of the framework may be made to receive platforms, gun mounts, fuselage, etc., as required for the character of the work which the machine is to be used.

If desired, a forward sustaining plane 88 may also be employed, and which is preferably at substantially the same elevation as the lower rear plane 74, and being of substantially the same length.

It will be noted that any one of the three tetrahedral portions of the framework shown combined in the present drawings, may be separated out and provide by itself an independent flying machine with all necessary parts.

It will also be apparent that a flying machine may be built up of a greater number of tetrahedral parts than the three shown in the drawings, and they may be overlapped in various modifications without departing from the spirit of the present invention.

It will be appreciated that the framework as herein described, is knitted together in an exceedingly strong and rigid combi-

nation, each of the parts of which is subjected to a minimum strain; and for this reason these parts may be constructed of material which is now the practice to reject as being unfit for aeroplane construction, and in this way that cautious selection which aeroplane construction now demands as respects its materials, is entirely eliminated in my present invention.

The words "tetrahedron" and "tetrahedral figure" in the claims are intended to mean either the complete geometrical figure, or merely sections or truncated figures.

It is obvious that those skilled in the art may vary the details of construction and arrangements of parts without departing from the spirit of my invention, and therefore I do not wish to be limited to such features except as may be required by the claims.

I claim:

1. In a flying machine, the combination of a framework built to resemble a tetrahedron, a series of curved sustaining planes mounted in stepped relation at the rear part of said framework, propelling means mounted in the forward part of said framework, a steering tail forming a projection of the lower part of said framework, and steering means carried on said tail, substantially as described.

2. In a flying machine, a framework built up in the figure of a tetrahedron, sustaining planes mounted in said framework, propelling means carried by said framework, a steering tail forming a projection of said framework and built in substantially tetrahedral form, and steering means carried by said tail, substantially as described.

3. A flying machine consisting of an open framework built up in substantially the shape of a tetrahedron, the top prism of the tetrahedral framework being removed, a sustaining plane mounted at the top of the framework substantially at the base of the removed prism, other sustaining planes mounted in the framework below the first-mentioned plane, propelling means mounted in the framework, a steering tail extending from the framework, and steering mechanism carried by such tail, substantially as described.

4. A flying machine composed of a framework built up in the form of a tetrahedral figure resting on one of the edges, the top prism extending at right angles to the lower edge being removed, a long sustaining plane mounted in the top of the framework at substantially the base of the removed prism, other progressively shorter sustaining planes mounted at various elevations in the framework below the first-mentioned plane, means carried by the framework whereby the machine may be propelled, a steering tail extending from said framework, steering means carried by said tail, and launching

85

95

100

110

120

125

and landing devices carried by said framework and tail, substantially as described.

5. A flying machine including a framework, said framework comprising members assembled together in tetrahedral formation with one edge lowermost and extending in the direction of travel, the top prism of the framework being left off, a series of sustaining planes of successively decreasing lengths mounted in stepped relation from the central top part of the framework downwardly toward the rear thereof, a sustaining plane also at the forward lower part of said framework, ground wheels at the lower edge of the framework, propelling mechanism disposed substantially centrally in the framework, and steering means connected to said framework.

6. A flying machine comprising a framework consisting of members assembled to form a plurality of tetrahedral figures, adjacent sides of the figures being overlapped, an edge of each figure extending lowermost and in the direction of travel, launching and landing devices carried at the lowermost edges of each of the tetrahedral figures comprising the framework, propelling means mounted in the framework, sustaining planes mounted in the framework, and steering means connected to the framework, substantially as described.

7. A flying machine consisting of a framework composed of members combined to form several associated tetrahedral figures with edges of each extending lowermost and in the direction of travel, parts of the sides of the figures being in common, the top prisms of the figures being removed, launching and landing devices carried by the lower edges of the figures, propelling means carried by each figure, a long sustaining plane extending across all of the figures at the top of the framework, other sustaining planes of lesser length also extending across all of the figures, a steering tail extending from the central figure, and steering means carried by such tail, substantially as described.

8. In a flying machine, the combination of a framework composed of edge members mounted to form a substantially tetrahedral figure, diagonal intersecting struts lying in the faces of the framework and connected between said edge members, horizontally extending tie-rods passing through the intersections of the struts and connected to said edge members, said tie-rods forming substantially rectangular frames within said tetrahedral framework, other tie-rods connected between said first named tie-rods, sustaining means mounted in said framework, propelling means also carried by said framework, launching and landing devices depending from the framework, a steering tail being a projection of a portion of the framework, and steering mechanism carried on said tail, substantially as described.

9. In a flying machine, the combination of a framework composed of edge members united to form a multiple-tetrahedral framework, diagonal intersecting struts lying in the faces of the framework and connected between said edge members, horizontally extending tie-rods passing through the intersections of the struts and connected to said edge members, said tie-rods forming substantially rectangular frames within said tetrahedral framework, other tie-rods connected between said first-named tie-rods, sustaining planes mounted in stepped relation in said framework, propelling means carried by each part of the framework representing a tetrahedron, floats carried at the lower edges of the several tetrahedral parts of said framework, ground wheels also carried at the lower edges of each tetrahedral portion of the framework, a steering tail being a projection of the central part of the tetrahedral framework, and steering mechanism carried on said tail, substantially as described.

90
In testimony whereof, I affix my signature.

JAMES C. CRITCHETT.
